HYDRAULIC DRIVE FOR REELS

Filed Feb. 3, 1941

UNITED STATES PATENT OFFICE

2,315,639

HYDRAULIC DRIVE FOR REELS

John C. Monahan, Royal Oak, Mich., assignor to
 Gar Wood Industries, Inc., Detroit, Mich., a
 corporation of Michigan

Application February 3, 1941, Serial No. 377,135

9 Claims. (Cl. 242—87)

The present invention relates to fluid motors and also relates to fluid motor drives for reels, and particularly for hose reels mounted on trucks.

One of the primary objects of the present invention is to provide a novel fluid motor construction in which the speed of the motor and the speed of a driven element associated with the motor are automatically controlled to move the driven element to a predetermined position while operating at one speed and thereafter operate at a different speed.

A further object of the invention is to provide a novel fluid motor construction in which a gear element, which is adapted to mesh with another gear element, is driven by the motor and in which the speed of the motor is automatically controlled so that it operates at a low speed while the gear is moved to mesh with the other gear, and thereafter operates at a higher driving speed.

Another object of the invention is to provide a reeling mechanism in which such mechanism may be driven by an hydraulic motor in one direction and may be operated by hand for free reeling in the opposite direction.

A further object of the invention is to provide a gear driving fluid motor construction in which the speed of the motor is automatically responsive to the position of the gear.

A further object of the invention is to provide an improved gear clutching and gear driving construction in which the gear is shifted to meshing position with another gear while driven by a fluid motor at one rate of speed, and, when in such position, the motor is automatically operated in response to such position to drive the gear at a different rate of speed.

Another object of the invention is to provide an improved reeling mechanism which is driven by a fluid motor so that such drive may be readily located in the desired position, such as an ordinarily inaccessible position in an automotive truck.

Other objects of the invention will become apparent from the following specification, the drawing relating thereto, and from the claims herein-after set forth.

In the drawing, in which like numerals are used to designate like parts in the several views throughout:

Figure 1 is a rear elevational view of an automotive tank truck having reeling mechanism according to the present invention associated therewith;

Fig. 2 is an enlarged, cross-sectional and plane

view taken substantially along the line 2—2 of Fig. 1;

Fig. 3 is an enlarged, cross-sectional view taken substantially along the line 3—3 of Fig. 2 and diagrammatically illustrating an hydraulic circuit and associated elements, operatively connected to the fluid motor; and

Fig. 4 is a view of the fluid motor similar to Fig. 3 and showing the parts in another position.

10 While the fluid motor and associated operating elements, according to the present invention, are here illustrated as being used for driving a hose reel mounted on an automobile tank truck, and while such motor and associated elements have 15 particular utility when so used, it will be appreciated by those skilled in the art that the fluid motor finds utility in many other places.

When used on a tank truck, a single hose or a plurality thereof are mounted on reels so that 20 when drawn out, the contents of the truck may be discharged at a considerable distance therefrom. Such hose are often as long at 150 to 200 feet, and are quite heavy, so that the winding of the hose onto the reel is a difficult job when done by hand, as is the present practice. According to 25 the present invention, power means are associated with the reel and are mounted on the vehicle so that the reel is free to rotate in order to pull the hose off the reel to make deliveries, and 30 power means are provided for re-winding the hose back onto the reel. Such power means include an hydraulic motor which is mounted on the truck adjacent the reel and which receives its power from flexible conduits leading to an hydraulic 35 pump and reservoir mounted on the truck in a convenient location, so that the pump may be driven from the power take-off of the transmission. By providing a fluid drive for the reel, flexible conduits may be used so that the motor 40 may be located in places which would be difficult or impossible to reach with a mechanical drive. Accordingly, the present invention provides a simplified means for driving the reel, together with a simplified manner of clutching the 45 driving element with a co-operating element on the reel. The fluid motor is provided with a self-acting clutch which automatically clutches-in on the reel when the power is applied with a predetermined valve setting and de-clutches when the 50 valve is shifted. Thus, the reel is free to be rotated by hand in unwinding the hose, when not operated by power.

Referring to the drawing, the rear end of an automotive tank truck 10 is illustrated with the 55 doors 12 thereof open and showing a pair of simi-

lar reels generally indicated at 14 mounted therein. While a pair of such reels is shown, it will be understood that the reels and driving means for each of such reels are similar to each other, so that a description of one will be sufficient for both.

The reel 14 includes a sheet metal drum or spool 16 having disc members 18 and 20 welded thereto, such disc members 18 and 20 being provided with central apertures 22 therethrough which receive therein a hollow axle or shaft 24. Shaft 24 is fixed to the disc members 18 and 20, preferably by welding, so that the spool 16 is driven with shaft 24. The shaft 24 is formed with a pair of spaced bearing portions 26 which are adapted to be received within bearings 28. Such bearings 28 may be suitably mounted to the tank body 10 by means of upstanding brackets 30, or the like, which are mounted on the body in the desired location. The hose 32 is adapted to be wound onto the reel, and has one end thereof connected to the reel in the usual way so that such end may communicate with the interior of the tank, such as through the hollow shaft 24 and through a suitable connection 34. Connection 34 extends to and communicates with the interior of the tank for emptying the contents thereof.

The structure so far described is conventional, and it will be appreciated that the hose may be unwound from the reel by pulling the free end thereof; and, in the past, the practice has been to re-wind the reel by hand.

According to the present invention, drive means are provided for driving the reel, and such means include a fluid motor generally indicated at 36. The fluid motor 36 may be of the vane or other type, but is here illustrated as being of the gear type having meshing gears 38 and 40 mounted within the housing, or casing, 42 in the usual way. The gear 40 may be an idle gear and the gear 38 a driven gear, and, in such event, the gear 38 is connected through a conventional speed reducer mechanism 44 with a drive shaft 46 for driving the same. A sliding gear 48 is keyed to the shaft 46 for sliding movement therewith but for rotation therewith.

The casing 42 is provided with an inlet port 50 having a valve 52, provided with an operating arm 53, associated therewith and having a passageway 54 which communicates with the inlet 50 when the valve 52 is in the position shown in Fig. 3. The passageway 54 leads to the inlet side of the gear elements 38 and 40 for the purpose of rotating such elements to drive the motor and, therefore, drive the gear 48. An outlet passageway 56 is formed in the casing 42 on the outlet side of the motor, and is adapted to communicate with a cylindrical bore 58, having an enlarged central portion 60 and having enlarged end portions 61 and 63 formed in the casing 42. The passageway 56 communicates adjacent the enlarged end 61 in an annular passageway. Another passageway 62 is formed in the casing 42 and communicates with the opposite enlarged end 63 of the chamber 58 and also with the inlet port 50 when the valve is so positioned as to permit such communication.

In order to shift the gear 48 from its idle position, as shown in Fig. 2, to a position so that it meshes with a drive gear 64, which is keyed to the shaft 24, a reciprocating, cylindrical plunger 66 is slidably disposed within the cylindrical chamber 58, and is of such a diameter that there are annular spaces between the surface of the

plunger and the walls of enlarged portions 60, 61, and 63 of the bore 58. Such plunger 66 has an outwardly projecting stem portion 68 which is slidably received through an aperture 70 formed in casing 42, and projects outwardly therebeyond. An engaging arm 72 is fixed to the outer end of the stem 68 and has a forked end 74 which is received within an annular groove 76 formed in the rear face of gear 48. It will thus be seen that as the plunger 66, together with the forked arm 72, is reciprocated, the gear 48 is correspondingly reciprocated into and out of mesh with the drive gear 64 which is keyed to shaft 24 for driving the reel.

15 An outlet port 78 is formed in the casing 42 and communicates with the chamber 58 through the enlarged central portion thereof.

The plunger 66 is formed with an L-shaped restricting passageway 80 in the end disposed within bore portion 61 so that such passageway 80 communicates with the end of the bore and also with the central enlarged portion 60. The passageway 80 is of predetermined size and is of such a size, smaller than passageway 56, that flow of fluid is restricted through passageway 80 to drive the gears at a slow speed, and a back pressure is built up behind the plunger in enlarged portion 61 to move the plunger to the left. A small groove 82 is formed in the opposite end 30 of the plunger which opens through the end thereof and provides constant communication between enlarged portions 60 and 63 to prevent an hydraulic lock as plunger 66 moves to the left. The groove 82 is of less area than the passageway 80 and is only large enough to prevent such lock.

Fluid under pressure is supplied the motor 36 for operating the same by means of a conventional hydraulic pump 84, which may be driven 40 from the power take-off of the engine in the usual way, as is done in the hydraulic hoist art. A tank or reservoir 86 is provided and contains a supply of operating fluid, preferably oil, and an inlet conduit 88 communicates with the interior of the tank 86 and with the inlet of the pump 84. A conduit 90 communicates with the outlet of pump 84 and communicates with the inlet port 50 of the motor 36. If desired, a pressure relief valve and by-pass line may be provided in the conduit 90 for the return of fluid directly to the tank in the event that the motor 36 is shut down, so that the pump 84 may be run continuously. A return line 92 communicates with the outlet 78 and returns the fluid to the tank 86.

Referring to Figures 3 and 4, with the valve 52 in the position shown and with the pump 84 operating, fluid under pressure is supplied conduit 54 and causes rotation of the motor elements 38 and 40 to drive the gear 48. The speed of such rotation will depend upon the rate of passage of fluid through the motor; and, with the plunger 66 in the position shown, the fluid discharging through passageway 56 will pass into enlarged portion 61 and be restricted in its passage through passageway 80 into the large portion 60. At the same time, a back pressure will be built up within enlarged portion 61 which will act on the right-hand end of plunger 66, thereby causing the plunger to move toward the left. The gear 48 will thus be driven at a relatively low speed and, at the same time, will be moved from its idle position into meshing position with gear 64, due to the movement of plunger 66. The plunger 66 is of such a length with respect to

the length of chamber 58 and the enlarged portion 60 thereof, so that when the plunger has moved a predetermined distance so that the gear 48 is in mesh with gear 64, the right-hand end of the plunger has passed beyond the annular shoulder 94 of the enlarged portion 60, so that unrestricted flow of fluid from passage way 56 into the discharge opening 78 is thereby permitted. This will cause a speeding-up of the motor elements 38 and 40, so that the gear 48 will operate at full driving speed.

With the valve in its neutral position, that is, a position turned counterclockwise 90° from that shown in Fig. 3, fluid under pressure will then also enter both of the passageways 54 and 62, so that the gear 48 continues to rotate, and such fluid will enter the enlarged portion 63 and act on the left end of the piston 66 to move it to the right and thus separate gears 48 and 64 from driving engagement.

Formal changes may be made in the specific embodiments of the invention described without departing from the spirit and substance of the broad invention, the scope of which is commensurate with the appended claims.

What is claimed is:

1. In combination, an hydraulic motor having a drive element, means associated with said motor providing a flow of fluid therethrough, a driven element operatively connected to said drive element to be driven thereby, movable means responsive to the fluid flow through said motor and operatively connected to said driven element for shifting said driven element to different positions, and means responsive to the position of said last named means for controlling the speed of said motor.

2. In combination, an hydraulic motor having a drive element, means associated with said motor providing a flow of fluid therethrough, a driven element operatively connected to said drive element to be driven thereby, movable means responsive to the fluid flow through said motor and operatively connected to said driven element for shifting said driven element from an idle position to an operating position, and means responsive to the movement of said last named means for controlling the speed of said motor so that said motor is operated at a low speed until said driven element is in said operating position and then said motor is operated at a higher speed.

3. In combination, a reel, means mounting said reel for free rotation, and power means operatively connectible with said reel for driving the same, said power means including a fluid motor having a drive element, a driven element operatively connected to said drive element to be driven thereby, means operatively connected to said driven element for shifting said driven element between an idle position out of connection with said reel and a position drivably connected with said reel, and means responsive to the position of said driven element for operating said motor at different speeds.

4. In combination, a reel, means mounting said reel for free rotation, a drive gear fixedly connected to said reel, and power means operatively connectible with said gear for driving the same, said power means including a fluid motor having a drive element, a driven gear operatively connected to said drive element to be driven thereby, means operatively connected to said driven gear for shifting said driven gear between an idle position and a position in mesh with said drive

gear, and means responsive to the position of said driven gear for operating said motor at different speeds.

5. In combination, a reel, means mounting said reel for free rotation, a drive gear fixedly connected to said reel, and power means operatively connectible with said gear for driving the same, said power means including a fluid motor having a drive element, a driven gear operatively connected to said drive element to be driven thereby, means operatively connected to said driven gear for shifting said driven gear between an idle position and a position in mesh with said drive gear, and means responsive to the position of said driven gear for operating said motor at a low speed until said driven gear is in mesh with said drive gear and for then operating said motor at a higher speed.

6. In combination, a truck, a reel, means mounting said reel on said truck, and power means mounted on said truck operatively connectible with said reel for driving the same, said power means including a fluid motor having a drive element, a driven element operatively connected to said drive element to be driven thereby, means operatively connected to said driven element for shifting said driven element between an idle position when said reel is free to rotate and a position drivably connected with said reel, and means responsive to the position of said driven element for operating said motor at different speeds.

7. In combination, an hydraulic motor including a casing having a rotary drive element mounted therein, inlet and outlet passages formed in said casing for the passage of operating fluid therethrough to rotate said element, a rotary driven element operatively connected to said drive element to be rotated thereby, means operatively connected to said rotary driven element for reciprocating said rotary driven element between an idle position and an operating position, said last named means including a reciprocating plunger movable in response to the passage of fluid through said outlet passage, said plunger being so constructed as to restrict the passage of fluid through said passageways in one position for operating said motor at a low speed and for permitting unrestricted flow through said passageways when in another position for operating said motor at a higher speed.

8. In combination, a pair of mateable toothed elements, means operatively connected to one of said elements for driving said one of said elements and for shifting said one of said elements into and out of mesh with the other of said elements, said last named means including an hydraulic motor having a drive element, means associated with said motor providing a flow of operating fluid therethrough, means operatively connecting said drive element with said one of said elements, movable means operatively responsive to the flow of fluid through said motor and connected to said one of said elements for moving said one of said elements into and out of mesh with the other of said elements, and means responsive to the position of said last named means for controlling the speed of said motor so that said motor is operated at a low speed until said one of said elements is in mesh with said other of said elements and then is operated at a higher speed.

9. In combination, a pair of mateable toothed elements, means operatively connected to one of said elements for driving said one of said ele-

ments and for shifting said one of said elements into and out of mesh with the other of said elements, said last named means including an hydraulic motor having a drive element, means associated with said motor providing a flow of operating fluid therethrough, means operatively connecting said drive element with said one of said elements, means operatively connected to said one of said elements for moving said one of said elements into and out of mesh with the other 10

of said elements, said last named means including a reciprocating plunger movable in response to the passage of fluid through said motor, said plunger being so constructed as to restrict the passage of fluid through said motor in one position for operating said motor at a low speed and for permitting unrestricted flow through said motor when in position for operating said motor at a higher speed.

JOHN C. MONAHAN.
